UNITED STATES PATENT OFFICE.

NELSON J. RUSSELL, OF CHICAGO, ILLINOIS.

FUEL-SAVING DEVICE.

Application filed April 26, 1926. Serial No. 104,599.

My invention pertains to fuel saving devices, and more particularly to such devices as are used in connection with boiler furnaces or similar furnaces, to feed air thereto and which are mounted in the flues thereof and which conduct the heat currents from the firebox to the smoke chamber of such boiler furnaces.

The main object of my invention is to provide an improved fuel saving device which can be readily mounted or installed in a boiler furnace and in the flues thereof, and which will receive atmospheric air, pre-heat the same, and conduct and discharge the atmospheric air into the heat currents issuing from the firebox and before such currents enter the flues on their passage to the smoke chamber and smoke stack. Another object is to provide such a device including a casing with outlet openings at one end placed adjacent the inlet end of a flue and including a pipe threaded in the opposite end of said casing and extending therefrom through the discharge end of said flue, into the atmosphere, said device preferably including means for closing the outlet end of said flue. And another object is to provide a casing with outlet openings and partition walls, and a compressor member mounted on said walls to diminish the interior space in said casing and to compress the air passing through the casing before it issues from the outlet openings.

Other objects and advantageous ends are accomplished with my invention, as will become apparent from the following description taken in connection with the accompanying drawings, in which,

Fig. 1 is a vertical longitudinal sectional view of a portion of a straight draft boiler furnace, showing a fuel saving device embodying my invention mounted in a flue, with its discharge end protruding from the flue;

Fig. 2 is a similar view of a return tubular boiler furnace, illustrating my invention applied thereto and mounted within the flue;

Fig. 3 is an enlarged longitudinal section through a flue with my invention mounted therein and the discharge end of the casing protruding from the flue;

Fig. 4 is a view similar to that shown in Fig. 3, and showing the operativeness and efficiency of the device, even though the protruding end of the casing is burnt off or broken away or otherwise damaged;

Fig. 5 is a cross section on line 5-5 of Fig. 3; and

Fig. 6 is an enlarged view similar to Fig. 3, but showing the discharge end of the casing mounted entirely within the flue.

In Fig. 1 of the drawings I have shown a form of my invention mounted in position in a boiler furnace 10 which includes the usual firebox 11 and grate 12 at the front of a boiler furnace and a smoke chamber 13 at the rear thereof leading to the smoke stack (not shown), said smoke chamber also serving the function of a combustion chamber in this type of furnace. A boiler portion or heating portion 14 communicates with the firebox 11 and includes a plurality of flues 15 for conducting the heated air and smoke, or the heat currents, from the firebox 11 to the smoke chamber 13. The furnace is also provided with the usual door 16 affording access to the firebox and to the flues and providing a fire door as well as a flue cleanout door.

My improved fuel saving device is mounted in one or more of these flues 15, and the device comprises a substantially cylindrical casing 17 provided with a perforated outlet portion or end 18, preferably tapering or conical in shape, and having outlet openings 19 provided around said tapering end, and an opening 19' on the narrowed end or point. This tapering portion is partially extended beyond the flue, as shown in Figs. 1 and 3. The opposite end of the casing is provided with a thickened end wall 20 or thickened in part and having a threaded opening for receiving the threaded end 21 of a pipe 22 which extends through the other end or discharge end of the flue and through the furnace wall, beyond the furnace, into the atmosphere.

I provide this casing with intersecting partition walls or members 23 which are stopped short of the end wall 20, to provide a space or chamber 24 between the end wall and the partition walls, thus permitting complete threading and entering of the pipe end 21 through the end wall 20 into said space 24. A compressor member 25 is provided on the partition walls 23, opposite space 24, and extends into tapering portion 18, for diminishing the cross section in said tapering portion, so as to compress and speed up the air as it passes through the casing and out of the outlet openings 19, to mingle with the heat currents traveling from

the firebox to the flues and there-through to the smoke chamber. A ring 26 is preferably placed around the pipe at the discharge end of the flue near the smoke chamber, for supporting the pipe and also for closing the flue at this end.

In Fig. 4 of the drawings is shown a casing having the outer part of the exposed tapering portion or end burnt away, thus indicating the operativeness and effectiveness of this type of casing, even when the exposed end has been destroyed, as the air will issue not only from such enlarged end opening, but will also continue to issue from the remaining outlet openings 19 and in a transverse direction, due to the compressor member 25, which is effective for compressing the air and directing it transversely through the openings 18, so as to properly mingle with the heat currents issuing from the firebox.

In Fig. 2 of the drawings is shown a boiler furnace in which the smoke chamber 13' is located at the front of the furnace, and the heat currents travel from the firebox 11' and the grate 12' rearwardly beneath the boiler portion or heating portion 14', to the combustion chamber 13'', and therefrom through the flues 15' into the smoke chamber 13' and up to the chimney. The usual door 16' is also provided to permit access to the flues and smoke chamber and for cleaning out of the flues.

The fuel saving device shown in this form is substantially the same as in the preceding form, including a casing 17 with tapering end 18 and discharge openings 19 and 19', and the thickened end wall 20 and partition wall 23 with a compressor member 25. The pipe 22 has its end 21 likewise threaded into end wall 20 and extends from the flue and beyond the furnace into the atmosphere. But in this form, as shown in Figs. 2 and 6, the tapering end 18 of the casing is mounted entirely within the inlet end of the flue, while at the outlet end of the flue the pipe 22 is supported by a ring 26 and said end of the flue is furthermore closed or sealed by sealing means 27, as cement or the like. This ring 26, as well as the sealing means 27, may be omitted from the device, especially where the perforated tapering portion 18 is extended from the flue, as shown in Figs. 1 and 3.

It is apparent from the foregoing disclosure that this fuel saving device is arranged and constructed so that it can be readily installed in the various types of boiler furnaces, by entering the casing through the usual fire-door or cleanout-door, and mounting it in the flue, while the air intake pipe is likewise insertable through said door and is extended through a hole provided in the furnace wall for this purpose, and is therefrom extended beyond the fur-

nace into the atmosphere, to take in the atmospheric air and lead it to the casing, said air being pre-heated in the pipe and in the casing and therefrom distributed through the outlet openings 19 against the heat currents arising from the firebox, in their passage to the flues and therefrom to the smoke chamber.

What I claim as my invention and desire to secure by Letters Patent is:

1. The combination, with a furnace having a firebox and flues for receiving heat currents from said firebox, of an air feeding casing with longitudinally extending intersecting partition walls mounted in one of the flues, a pipe extending from said casing through the flue and beyond the furnace into the atmosphere, and a tapering portion with outlet openings on said casing and placed adjacent the receiving end of said flue for spreading and exposing the air from said casing to the heat currents before they enter the flues.

2. The combination, with a furnace having a firebox and flues for receiving heat currents from said firebox, of an air feeding casing mounted in one of said flues, and having longitudinal intersecting partition walls, and a compressor member on the intersecting part of said walls to diminish the space at the discharge end of said casing and thereby compressing the air in its passage through the casing and through the outlet openings thereon.

3. The combination, with a furnace having a firebox and flues for receiving heat currents from the firebox, of an air feeding casing mounted in the receiving end of one of said flues and having a tapering portion with outlet openings located adjacent said receiving end of the flue, a compressor block in said casing adjacent said tapering portion for compressing the air in the passage through said casing out of the outlet openings, and a pipe extending from the opposite end of said casing out of the furnace into the atmosphere.

4. A fuel saving device for a furnace with tubular flues, said device comprising a casing with outlet openings at one end and a thickened wall with a threaded opening at the opposite end, an inlet pipe threaded into said end wall, and partition walls extending longitudinally through said casing to divide it into sections and stopping short of said end wall and forming a space therewith to permit complete threading and entering of the pipe end through said end wall and into said space.

5. A fuel saving device for a furnace with tubular flues, said device comprising a casing with a tapering portion having outlet openings at one end, a thickened wall with a threaded opening positioned at the opposite end of said casing, an inlet pipe threaded

into said threaded opening, longitudinal partition walls in said casing stopping short of said end wall and forming a space therewith to permit complete threading and entering of the pipe end through the end wall into said space, and a compressor member on said partition walls located in said

tapering portion for diminishing the space therein to compress the air in its passage through said tapering portion and through 10 the outlet openings thereon.

In testimony whereof I have signed my name to this specification.

NELSON J. RUSSELL.
